Primary Examiner — T. Chase Nelson*Assistant Examiner* — Mark Cavanna(74) *Attorney, Agent, or Firm* — Robert H. Eichenberger;
Scott W. Higdon; Middleton Reutlinger**CLAIM**

The ornamental design for a sleep aid, as shown and described.

DESCRIPTION

FIG. 1 is a front left side perspective view of a first embodiment of a sleep aid showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof;

FIG. 8 is a front left side perspective view of a second embodiment of the sleep aid of my design;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken lines showing environmental structure are for illustrative purposes only and form no part of the claimed design.
